UNITED STATES PATENT OFFICE.

WILLIAM W. LASKER, OF BROOKLYN, NEW YORK, ASSIGNOR TO POWERS ACCOUNTING MACHINE CORPORATION, OF NEW YORK, N. Y., A CORPORATION OF DELAWARE.

AUTOMATIC CIRCUIT BREAKER FOR ELECTRIC KEY PUNCHES.

Application filed April 29, 1925. Serial No. 26,688.

The present invention relates to card punching machines for perforating record cards in a predetermined manner, and relates more particularly to a circuit breaking means for electrically operating punch mechanisms.

Some of the objects of the present invention are to provide means functioning in conjunction with a traveling carriage electrically operated set-up mechanism for card punches to prevent the set-up mechanism or any part thereof from operating during the return of the carriage after a set-up operation; to provide means for automatically rendering a control circuit or circuits for a punch set-up ineffective at a predetermined time; to provide means controlled by the carriage return of a key punch carriage for breaking the circuit which operates the punch set-up under operating conditions; to provide means for automatically breaking the circuit of a punch set-up control at the beginning of the return of the pin carriage, and to automatically close such circuit at the end of the return of the pin carriage; and to provide other improvements as will hereinafter appear.

In the accompanying drawings Fig. 1 represents a side elevation of a portion of a punching machine showing one form of the present invention applied thereto; and Fig. 2 represents an end elevation of the same.

Referring to the drawings, a bracket 10, forming a part of the main frame of a key operated punching machine for perforating record cards, is shown having an angle support 11 attached thereto to carry a contact arm 12 and a contactor arm 13 which are insulated from each other by a strip of insulation 14 and from the support 11 by insulation bushings 14' through which pass the mounting screws 15. The contact arm 12 is of conducting material and forms with its contact 16 one terminal of a circuit of which the conductor 17 is a part. The contactor arm 13 is also of conducting material and forms with its contactor 18 the other terminal of the same circuit and of which conductor 20 is a part. The two conductors 17 and 20 are preferably in the common return of the plurality of circuits which function respectively to selectively operate the set-up mechanism of the punching machine.

As shown in Fig. 1 the circuit including the conductors 17 and 20 is closed at the contact 16 and the contactor 18, this

being the normal condition when the punching machine is making a set-up for a punching operation. Generally considered, this type of card punching machine operates through the manual selection and operation of keys which transmit motion to selecting pins respectively in a carriage which travels by a step by step movement across a set-up mechanism consisting of a bank of pins corresponding in number and arrangement to the data positions on the record card. Those pins set up by the selecting pins of the moving carriage remain so set until all of the data positions for a card are set up and then the punch key is operated so that all of the punches to be actuated are caused to function. In the machine to which the present invention has been applied by way of example the keys of the keyboard are arranged to close electrical circuits so that the movement of any selected key is transmitted electrically to the selected pins of the movable carriage. Following its set up movement the carriage is automatically returned to its initial position ready to again travel across the set-up mechanism as the keys are operated for another card. This return of the carriage in the present instance is effected mechanically through the release of a link 21 by the disengagement of a latch bar 22 from a pin 23. The latch bar 22 is pivoted at 24 to the bracket 10 and is normally held in latching position by a spring 25 interposed between a pin 26 of the bar 22 and a pin 27 of the bracket 10. The opposite end of the latch bar 22 is bifurcated as shown at 28 to straddle a pin 30 which is fast to the core 31 of a solenoid 32. The solenoid 32 is connected by conductors 33 and 34 to a control circuit which is arranged to be closed by the carriage return key of the punch keyboard. When the carriage return key is operated the circuit through the solenoid 32 is closed and the latter energized to rock the latch bar 22 against the tension of the spring 25 to release the link 21 for movement under the pull of a control spring 35. The movement of the link 21 simultaneously swings two arms 36 and 37, the former 36 being fixed to a rock shaft 38 by which the carriage return clutch is thrown in, while the latter 37 is fixed to a reset shaft 40 by which the link 21 is returned for reengagement with the latch 22.

In order to break the contact between the 110

2

contactor 18 and the contact 16, the contactor arm 13 is extended, as shown at 41, beyond the arm 12 and into the path of a pick-up member 42 secured by a screw 43, or the like, 5 to the link 21, the arrangement being such that the member 42 allows the contactor arm 13 to normally hold its contactor 18 in circuit closing position, but when the link 21 is unlatched and released the contact will 10 be broken so that the common return for all punch set up circuits will be interrupted during the entire time the carriage is making its return. In this way the possibility of any of the selecting pins of the carriage being 15 actuated on the return movement to cause breakage and damage is entirely overcome.

From the foregoing it will be apparent that a complete unitary control has been provided for the actuating circuits of a punch- 20 ing machine whereby all such circuits are rendered ineffective during the return of the set-up control carriage to its initial position. Also when the carriage has returned and before it can function to start a new set-up in 25 the punch mechanism all the circuits are automatically closed at the point controlled by the contact 16 and the contactor 18. This leaves the circuits in operating condition so that when any key of the keyboard is operated, 30 the circuit including that key will be closed to make a set-up for the operation of the punch corresponding to the key operated. By the provision of an auxiliary break in the common return of all of the punch 35 control circuits, which becomes effective during the return of the carriage, it will be evident that the depression of the keys of the keyboard during this return interval will have no effect upon the set-up mechanism. 40 Otherwise the depression of keys during the carriage return would cause set-up pins to be projected while the carriage was running and serious damage would be the result.

45 While only a single form is shown in which this invention may be embodied, it is to be understood that the invention is not limited to any specific construction, but might be applied to various forms without departing from the spirit of the invention 50 or the scope of the appended claims.

Having thus described my invention, I claim:

55 1. In an electric punch mechanism, the combination of a control circuit for controlling a punch mechanism on a movable carriage, and means for opening and maintaining said circuit open on the return movement of said carriage.

60 2. In an electric punch mechanism, the combination of a circuit return common to a plurality of circuits for respectively controlling a punch mechanism on a movable

carriage, and means for automatically opening and maintaining said common return open on the return movement of said carriage. 65

3. In an electric punch mechanism, the combination of a circuit return common to a plurality of circuits for respectively controlling a punch mechanism on a movable carriage, means automatically opening said circuit return at a predetermined time in the travel of said carriage, and means to close said circuit return at another predetermined time in the travel of said carriage. 75

4. In an electric punch mechanism, the combination of a control circuit for controlling a punch mechanism on a movable carriage, and means including a carriage return device for opening said circuit during the return of said carriage. 80

5. In an electric punch mechanism, the combination of a control circuit for controlling a punch mechanism on a movable carriage, and means including a solenoid actuated latch for opening said circuit during the return movement of said carriage. 85

6. In an electric punch mechanism, the combination of a circuit return common to a plurality of circuits for respectively controlling a punch mechanism on a movable carriage, and means including a carriage return device for opening said return circuit during the return of said carriage. 90

7. In an electric punch mechanism, the combination of a circuit return common to a plurality of circuits for respectively controlling a punch mechanism on a movable carriage, a reset lever for said punch mechanism, means for actuating said reset lever, 100 and means operated by said reset lever for breaking said return circuit whereby said circuits are all open during the return movement of said carriage. 105

8. In an electric punch mechanism, the combination of a circuit return common to a plurality of circuits for respectively controlling a punch mechanism on a movable carriage, a contact forming one terminal of said circuit return, a contactor forming the 110 other terminal of said circuit return and normally engaging said contact to maintain said circuit closed at that point, a reset lever, means on said lever arranged to move in a path to shift said contactor and move 115 it to break said return circuit, and means to actuate said lever to cause said shift means to function whereby said circuits are maintained open during the return of said carriage. 120

Signed at Philadelphia, county of Philadelphia, State of Pennsylvania, this 20th day of April, 1925.

WILLIAM W. LASKER.
